UNITED STATES PATENT OFFICE.

GEORGE H. AKRIDGE, OF HARTSFIELD, GEORGIA.

SASH HOLDER AND FASTENER.

No. 823,659.

Specification of Letters Patent.

Patented June 19, 1906.

Application filed October 2, 1905, Serial No. 281,042.

To all whom it may concern:

Be it known that I, GEORGE H. AKRIDGE, a citizen of the United States, residing at Hartsfield, in the county of Colquitt and State of Georgia, have invented certain new and useful Improvements in Sash Holders and Fasteners, of which the following is a specification.

For a full description of the invention and the merits thereof and also to acquire a knowledge of the details of construction of the means for effecting the result reference is to be had to the following description and accompanying drawings, in which—

15 Figure 1 is a vertical section showing a sash in closed position and a fastener embodying the invention in a position holding said sash closed. Fig. 2 is a view similar to Fig. 1, the sash being raised to the limit of its upward movement. Fig. 3 shows the fastener or holder coöperating with the sash, the latter arranged in a position intermediate its extremes of movement.

25 Corresponding and like parts are referred to in the following description and indicated in all the views of the drawings by the same reference characters.

The invention consists of a novel form of sash holder or fastener for windows.

30 In the drawings the numeral 1 designates the window-frame, and the numeral 2 a window-stop.

The numeral 3 denotes the sash, and the numeral 4 the fastener or holder, comprising a 35 invention. The fastener 4 comprises a dog pivoted near one end, as shown at 5, the opposite end of the dog being adapted to contact with the sash 3 in order to hold the same in a predetermined position. The dog is 40 pivoted between its ends to the window-stop, and the longer end of the dog is formed at its outer extremity with a hook 6, adapted to engage over the top rail of the sash 3 in order to lock said sash down in closed position.

45 The opposite end portion of the dog 4 is formed with a notch 7, said notch being adapted to receive the lower rail of the sash when said sash is raised into the position shown in Fig. 2. In this instance the dog

will be disposed in an approximately vertical 50 position and will rigidly support the sash in the open position before described.

The formation of the notch 7 is such as to provide spaced points 8 adjacent thereto, and these points are adapted to bite into one 55 of the side or vertical bars of the sash-frame in order to position the sash and hold the same securely when it is disposed at a point between its extremes of movement. Fig. 3 shows the points 8 engaging with the sash as 60 above mentioned, and, if desirable, the bar, which is engaged by the points 8, may be formed with a vertical kerf or recess to receive an engaging plate or like means to take up wear caused by the coaction of the 65 points 8.

It will be understood that when the window-sash 3 is down in closed position at one extreme of its movement the hook 6 will engage over the top rail of the sash on pivotal 70 movement of the fastener 4, and said sash will be held closed. When the sash is at the opposite extreme of its movement or raised to open the window, the notch 7 coacts to support the sash, as before premised. The 75 points 8 engage the sash only when the same is arranged in an intermediate position.

The device consists of a single part which may be very cheaply manufactured and which when secured in position on a window-frame will effectively hold the window-sash in the desired position. The member 4 is 80 also readily operable to accomplish its functions, and this is a desirable feature in a device of this class.

Having thus described the invention, what is claimed as new is—

In a sash-fastener, the combination of a window-frame, and a sash movable therein, of a pawl or dog 4 pivotally mounted near one end on the window-frame, said dog being provided at one end with a hook facing the pivot and at its other end with an angular notch slightly offset from the pivot and facing away from the same, the edges of the said 90 notch providing biting surfaces and the notch and hook also facing in opposite directions with respect to the median line of the 95

dog, the hook at one end of the dog being designed to take over the upper edge of the window-sash to prevent the same from being raised, the angular notch being designed to receive the lower edge of said sash whereby to sustain the sash in a raised position and the edges of the notch providing means for biting into a side of the sash whereby to sus-

tain the latter in an intermediate position, as and for the purpose set forth.

In testimony whereof I affix my signature in presence of two witnesses.

GEORGE H. AKRIDGE. [L. s.]
